UNITED STATES PATENT OFFICE.

THOMAS E. COPELIN, OF CHICAGO, ILLINOIS.

MACHINE FOR MAKING STICK - CANDY.

SPECIFICATION forming part of Letters Patent No. 313,061, dated March 3, 1885.

Application filed July 5, 1884. (No model.)

To all whom it may concern:

Be it known that I, THOMAS E. COPELIN, a citizen of the United States, residing at Chicago, in the county of Cook and State of Illinois, have invented certain new and useful Improvements in Machines for Making Stick-Candy, of which the following, in connection with the accompanying drawings, is a specification.

10 In the drawings, Figure 1 is a side elevation of my improved candy-machine embodying my invention. Fig. 2 is a section on the line $\alpha\alpha$ of Fig. 1, looking in the direction indicated by the arrow.

15 Like letters of reference indicate like parts. The object of my invention is to make a square stick of candy, and I accomplish this, as will hereinafter more fully appear.

20 In the drawings, $A A$ are suitable standards or bearings for the rollers B and B' , and on one end of the rollers B and B' are pinions $C C$, meshing into each other, and on one end of the spindle of the roller B , I have a crank or handle, D , to give motion to the rollers B and B' .

25 On the roller B , I cut a groove, a , and a corresponding groove, a' , on the roller B' , each groove being twice as wide as it is deep; and it will be clearly seen by reference to Fig. 1 in the drawing that when the groove a is placed correspondingly above the groove a' it forms a complete square hole or opening. On the face of the groove of the roller B , I have small pins or projections, b , as shown.

30 35 I do not here intend to restrict myself to one

groove only on the rollers, as a series of them can be used with equal facility.

The operation is as follows: In making candy, after the material is ready to be formed into sticks it is first rolled and worked by hand into long round strips about three-fourths of an inch in thickness, and it is then ready, by using my machine, to be formed into a square stick of candy. I feed the material into the opening on the rollers, and by turning the handle D revolve the rollers, and the projections b on the upper face of the opening grasps the material and aids in pulling the material through with greater facility. It will be clearly seen that after the material passes through the opening it issues in the form of a perfectly square stick of candy, and the same can then be cut in suitable lengths.

Having thus described my invention, what I claim as new, and desire to secure by Letters Patent, is—

1. In a candy-machine, the combination of the rollers B and B' , having corresponding grooves, a and a' , to form a square, as and for the purposes specified.

2. In a candy-machine, the combination of the rollers B and B' , having corresponding grooves, a and a' , the face of one or both of said grooves having pins or projections b , as and for the purposes described.

THOMAS E. COPELIN.
